Primary Examiner—Robert M. Spear*Assistant Examiner*—Mary Ann Calabrese(74) *Attorney, Agent, or Firm*—Thomas, Kayden, Horstemeyer & Risley, LLP(57) **CLAIM**

The ornamental design for a baseball cap with rear opening, as shown and described.

DESCRIPTION

FIG. 1 is a perspective view of the baseball cap with rear opening, showing my new design;

FIG. 2 is a left side view of the baseball cap with rear opening shown in FIG. 1;

FIG. 3 is a top view of the baseball cap with rear opening shown in FIG. 1;

FIG. 4 is a right side view of the baseball cap with rear opening shown in FIG. 1;

FIG. 5 is a bottom view of the baseball cap with rear opening shown in FIG. 1;

FIG. 6 is a front view of the baseball cap with rear opening shown in FIG. 1; and,

FIG. 7 is a back view of the baseball cap with rear opening shown in FIG. 1.

In the drawings, the broken lines are for illustrative purposes only and form no part of the claimed design.
